UNITED STATES PATENT OFFICE.

EDWARD E. BRADLEY, OF STONINGTON, CONNECTICUT, ASSIGNOR TO THE ATWOOD-MORRISON COMPANY, OF STONINGTON, CONNECTICUT, A CORPORATION OF NEW JERSEY.

GUIDE-MOTION FOR QUILL-WINDING MACHINES.

No. 922,848.

Specification of Letters Patent.

Patented May 25, 1909.

Application filed October 2, 1906. Serial No. 337,135.

To all whom it may concern:

Be it known that I, EDWARD E. BRADLEY, a citizen of the United States, and resident of Stonington, in the county of New London 5 and State of Connecticut, have invented a new and useful Improvement in Guide-Motions for Quill-Winding Machines, of which the following is a specification.

My invention relates to quill winding machines and more particularly to the guide motion for laying the thread on the quill and comprises a two-part spindle in which the one part is continuously driven and the other part is provided with gear independently of neighboring spindles and the reciprocating motion of the rod which carries the guide feed roller is operated by a cam driven by said gear.

It also contemplates a guide-eye for the thread arranged so as to be reciprocated by the rod which carries the guide roller and bodily shifted by the guide roller as it moves along said rod.

My invention further consists in certain features of construction and combination of parts as will be hereinafter described and pointed out in the claims.

In the accompanying drawings, Figure 1 is a partial side elevation of a machine showing several of the spindles in position thereon, Fig. 2 is a vertical section in the plane of the line A—A of Fig. 1, Fig. 3 is an enlarged view in side elevation of the spindle and parts immediately connected therewith, Fig. 4 is a top plan view of the same, Fig. 5 is an end view of the same, and Fig. 6 is a vertical longitudinal section in the plane of the line B—B of Fig. 4.

The head frame which supports the series 40 of spindles is denoted by 1 and may be of any well known or approved form.

The belt for driving the two series of spindles is denoted by 2 and is driven from a suitable source of power, not shown. This 45 belt passes, as is common, between the pulleys 3 and 4 on the inner ends of the spindles as clearly shown in Fig. 2.

The rear part of the spindle, which carries the pulley 4, is denoted by 5 and the forward 50 part which receives the quill is denoted by 6.

The part 5 is mounted in a stationary portion 7 of the frame and has fixed to rotate

therewith a clutch member 8 which is adapted to be engaged by a sliding clutch member 9 carried by the part 6 of the spindle and while fixed by some suitable ordinary means to rotate therewith, as, for example, by a feather and groove connection, is permitted a sliding motion on the part 6 into and out of engagement with the member 8.

The quill carrying part 6 of the spindle is mounted in a frame 10 hinged at 11 to the stationary part of the frame so as to permit the part 6 of the spindle to be bodily tilted 65 toward and away from the feed guide roller.

The clutch member 9 is slid toward and away from the clutch member 8 by means of a shifting arm 12 attached to a sliding bar 13, the latter being provided with a spring 14 70 tending to throw the bar in a position to release the clutch member 9 from the clutch member 8, the said bar 13 being further provided with a hand piece 15 for forcing the bar inwardly to bring the clutch members 75 into engagement against the tension of the spring 14.

A swinging frame 10 in which the quill carrying part of the spindle is mounted is also under the influence of a torsion spring 80 16 tending to swing the frame and spindle carried thereby toward the feed guide roller to be hereinafter described.

The part 6 of the spindle is further provided with a pinion 17 fixed thereon in position to engage a gear wheel 18 fixed to a rotary shaft 19 mounted in suitable arms 20 and 21 projecting upwardly from the stationary portion of the spindle frame.

The gear 18 has fixed to rotate therewith a cam 22 which engages a bearing 23 carried by the reciprocating rod 24 the latter being mounted as usual in the stationary part of the spindle frame.

The rod 24 is under spring tension by means of a spring 25 tending to throw it outwardly as far as the cam 22 will permit it and the cam forces the rod inwardly against the tension of the spring 25.

The outer part of the reciprocating rod is 100 screw threaded as at 26 and on the screw threaded portion of the rod the feed guide roller 27 is loosely mounted and is caused to travel along a threaded portion 26 by means

of a spring latch 28 which normally occupies the position shown in full lines, Fig. 3, with its end in engagement with the screw threads.

When desired to move the feed roller back and forth along the rod 26 independently of the screw threads, the latch 28 may be tilted back into the position shown in dotted lines, thus freeing the feed guide roller from the threads.

10 A guide-eye 29 for directing the threads to the quill projects from a socket piece 30 arranged to slide on a rod 31 set in the arm 21 of the frame, the said socket 30 being provided with a bifurcated arm 32 which engages a groove 33 in the hub of the guide roller 27 so as to cause the socket 30 and hence the guide-eye 29 to travel bodily along with the feed guide roller while, at the same time, permitting the feed guide roller to rotate independently of the socket piece.

An arm 34 has a hub 35 through which the reciprocating rod 24 passes and to which the rod 24 may be locked in the desired rotary adjustment by means of a set screw 36 which extends through the hub of the arm into engagement with the rod. The arm 34 also embraces the rod 31 to hold the arm against rocking motion. The object of this arm is to adjust the guide roller bodily nearer to or farther away from the quill and this is provided for by making the screw threaded portion 26 of the rod 24 eccentric to the rear part of the rod.

The hand piece 15 is locked in its position to hold the clutch members engaged by means of a lug 37 projecting from its side in position to engage a spring actuated latch 38. The latch 38 may be operated to release the clutch members by means of a depending arm 39 which may be pushed by the finger of the operator.

To swing the quill carrying part of the spindle away from the feed guide roller when it is desired to remove the quill, the hand piece 15 is provided with a lug 40 which projects upwardly therefrom and engages the face of a lug 41 depending from the front portion of the swinging frame 10 which carries the front portion of the spindle. There is also arranged to coact with the lug 40 an adjusting screw 42 engaged in a lug 43 uprising from the hand piece 15 on the opposite side of the lug 41.

In operation, assuming the rear part 5 of the spindle to be continuously operated by its pulley 4 when the hand piece 15 is pushed inwardly to bring the clutch members 8 and 9 into engagement, the front or quill carrying part of the spindle will be set to rotating and this will start the gear wheel 18 carrying the cam 22 which latter, in its rotary movement, will produce a reciprocating movement of the rod 24 and as often as the guide feed roller 27 comes in contact with the

wound thread it will be given more or less of a turn to cause it to gradually travel along the screw threaded portion 26 of the reciprocating rod to lay the thread on the quill. When the quill is wound the operator may stop the further winding by simply pressing 65 on the arm 39 and thereby releasing the latch 38 and permitting the hand piece to spring outwardly under the tension of its actuating spring 14 thereby releasing the clutch members and, at the same time, bringing the clutch member 9 into engagement with the end of the pinion 17 forcing it against the frame 10, thereby putting a friction brake on the further rotary movement of the front part 6 of the spindle. This outward movement of the rod 13 carrying the hand piece 15 will, at the same time, by the engagement of the lugs 40 and 41, tilt the part 6 of the spindle outwardly into position to have the filled quill removed and a new one put in place.

As the hand piece is pushed inwardly to bring the clutch member into engagement, it will, at the same time, tilt the outer portion 6 of the spindle back into parallelism 90 with the reciprocating rod carrying the guide feed roller and this parallelism may be maintained at the start and during the wear of the spindle mechanism by means of an adjusting screw 44 engaged in a lug 45 on the swinging frame 10 and engaging a lug 46 on the stationary frame of the spindle.

What I claim is:—

1. In a quilling spindle comprising a front spindle section mounted to tilt, a rear spindle section, means for connecting and disconnecting the sections, a reciprocating guide feed roller, a cam for reciprocating the roller and means for operating the cam from the front spindle section.

2. A quilling spindle comprising a front spindle section mounted to tilt, a rear spindle section, means for driving the rear spindle section continuously, means for connecting and disconnecting the front spindle section to and from the rear spindle section and a guide feed roller under the control of the front spindle section to be bodily moved back and forth.

3. A quilling spindle comprising a rear continuously driven section, a front quill receiving section mounted to tilt, means for connecting the quill receiving section to and disconnecting it from the rear section, a reciprocating rod, a guide feed roller carried by the rod and a cam geared with the front spindle section for reciprocating the rod.

4. In combination, a two-part spindle, means for continuously driving one of the parts, means for tilting the other part, means for locking the other part to and means for releasing it from the continuously driven part, a reciprocating rod, a guide feed

roller mounted on the reciprocating rod, a cam controlled by the front spindle section for reciprocating the said rod, and a thread eye engaged with the guide feed roller and 5 mounted to slide back and forth in unison with the roller.

In testimony, that I claim the foregoing as

my invention, I have signed my name in presence of two witnesses, this 13th day of September, 1906.

EDWARD E. BRADLEY.
